UNITED STATES PATENT OFFICE.

MINNIE F. DAVIS, OF TOPEKA, KANSAS.

DESIGN FOR A SHOE-FITTING STOOL.

Application filed December 15, 1921. Serial No. 522,714. Term of patent 14 years.

To all whom it may concern:

Be it known that I, MINNIE F. DAVIS, a citizen of the United States, residing at Topeka, in the county of Shawnee and State of Kansas, have invented a new, original, and ornamental Design for a Shoe-Fitting Stool, of which the following is a specification, reference being had to the accompanying drawing, forming part thereof.

In the drawings:

Figure 1 is a perspective view of a shoe fitting stool having my new design, and Fig. 2 is an end elevation view of the same.

I claim:

An ornamental design for a shoe fitting stool, substantially as shown.

Mrs. MINNIE F. DAVIS.
